UNITED STATES PATENT OFFICE

LUTHER ACHAN DAY, OF SHERMAN, TEXAS, ASSIGNOR TO DAY MANUFACTURING COMPANY, OF SHERMAN, TEXAS, AND THE JUSTIN LEATHER GOODS COMPANY, OF NOCONA, TEXAS

DISPLAY BOX

Application filed February 12, 1931. Serial No. 515,295.

This invention relates to a box for holding small leather articles and novelties, one of the objects being to provide a container which will hold its contents securely and, when opened, will constitute an attractive means for displaying the held article or articles to best advantage.

Another object is to provide a box of this character which requires less space for effective display in show cases or windows than do boxes ordinarily employed.

A further object is to provide a box having more than the usual rigidity so that it can be used longer than most boxes and will always present an attractive appearance.

Another object is to provide a display box which is designed to hold one or more articles in the body of the box while one or more additional articles are held in the cover, the said box, when opened, serving to display all of the articles contained therein.

Another object is to provide a box so constructed as to enable the prospective purchaser to examine the entire contents of the box without removing any article therefrom, thereby preventing soiling of the articles through handling.

With the foregoing and other objects in view which will appear as the description proceeds, the invention resides in the combination and arrangement of parts and in the details of construction hereinafter described and claimed, it being understood that changes in the precise embodiment of the invention herein disclosed may be made within the scope of what is claimed, without departing from the spirit of the invention.

In the accompanying drawings, the preferred form of the invention has been shown.

In said drawings:

Figure 1 is a front elevation showing the box open and displaying an article in the top thereof.

Figure 2 is a side elevation.

Figure 3 is a section on line 3—3, Figure 2.

Figure 4 is a vertical section through the closed box taken from front to rear.

Figure 5 is a section on line 5—5, Figure 4.

Figure 6 is a perspective view of the insert used in the cover portion of the box.

Figure 7 is a perspective view of the insert used in the body portion thereof.

Referring to the figures by characters of reference, 1 designates the body of the box which can be made with a projecting shoulder 2 formed by extended portions of the bottom plate 3. The body is provided with outer wall panels 4 the upper edges of which terminate below the corresponding edges of the box body to form an exterior shoulder 5 extending continuously around the box.

The cover includes the box-like body 6 so proportioned as to bear upon the shoulder 5. The walls of the body 6 have outer panels 7 attached thereto and projecting above body 6 to form a recess 8 in which is fastened a padded top panel 9. The back face of the bottom and cover portions of the box are hingedly connected in any suitable manner as by means of a fabric 10 affixed thereto.

Arranged within the body 1 of the box is a die-cut insert 11 having one or more openings 12 so proportioned as to receive the article or articles to be displayed in the body portion. A piece of satin, silk or any other attractive material is extended loosely over the insert as shown at 13 and has its edge portions glued to the walls of the insert and to the inner surface of the adjacent portions of the body 1. The central slack portion of this covering is pressed through the opening 12 so as to be supported in the space surrounded by the insert, thereby to form a pocket 14. Obviously it becomes necessary to crumple the fabric in order to bring it to the position shown in Figures 4 and 5 and this will present an attractive appearance as will be apparent by referring to Figures 1 and 3.

The insert with its cover 13 is located below the upper edges of the body 1.

Another die-cut insert 15 is arranged within the cover 6 and has one or more openings 16 for the reception of an article or articles to be displayed. A covering 17 of an attractive fabric is placed over this insert and has its edge portions secured to the walls of the insert 15 and to the inner surface of the cover 6. That portion of the fabric 17 arranged across the opening or openings 16 is

pressed back into the space surrounded by the insert, thereby to form a pocket 18. The fabric will of course be formed into irregular folds which add materially to the attractiveness of the article.

A band 19 of elastic or the like can have its ends secured between the insert 11 and the body 1 and can be extended diagonally or in any other direction across the pocket 14. 10 Another band of elastic or the like, indicated at 20, can be similarly fastened between the insert 15 and the wall cover 6 and extended in any desired direction across the pocket 18.

For the purpose of supporting the cover 15 in an upwardly extended or open position, a stop strap 21 of tape, ribbon or the like can be secured to the inner surfaces of the body 1 and cover 6 at its ends, as shown in Figure 2.

As before stated the openings 13 and 16 20 are so proportioned as to properly receive the articles to be displayed. These articles can be in the nature of small items of leather or novelties. In the drawings, a wallet W has been shown supported in the pocket 14 25 while a card case or purse P has been shown in the pocket 18. Each of these articles is adapted to be thrust through the opening provided therefor after being inserted under its retaining band. After it has been pushed 30 back into its pocket it will be held frictionally by the fabric forming the pocket and one or more edge portions of each inserted article will expand back of one or more walls of the opening in which the article has been 35 inserted so that the article will thus be retained not only by the band extending there-across but also by the overlying walls of the opening. The fabric covering arranged 40 about the engaged article will form an attractive border or frame for the article whereby said article may be displayed to best advantage.

When the box is closed the two articles will 45 be held properly in their respective pockets and by opening the box to the position shown in Figure 2, all of the articles therein will be displayed to the customer and can be readily inspected without handling.

What is claimed is:

50 1. A display box including a body, a cover, inserts secured in the body and cover respectively and having openings through which articles to be displayed are adapted to be forced, a fabric covering for each insert having a portion extending through the opening therein and under the walls of the opening to constitute an article holding pocket the length and width of which are greater 55 than the length and width of the opening, and a retaining band extending across each opening, the walls of the openings constituting means for lapping the corresponding edge portions of the inserted articles to retain 60 them in the pocket, said pocket being small enough to support the inserted article close to

and substantially parallel with the apertured face of the insert.

2. A display box including a member having walls at all sides thereof, an insert secured in said member and having an opening through which an article to be displayed is adapted to be forced, a fabric cover for the insert having a portion extending through the opening and under all of the walls of the opening to constitute an article holding pocket the length and width of which are greater than the length and width of the opening, all of the walls of the opening constituting means for lapping the corresponding edge portions of the inserted article to retain it in the pocket, said pocket being small enough to support the inserted article close to and substantially parallel with the apertured face of the insert.

In testimony that I claim the foregoing as my own, I have hereto affixed my signature.

LUTHER ACHAN DAY.
